UNITED STATES PATENT OFFICE.

CALVIN DAVID PAXSON, OF LIMAVILLE, OHIO.

RAILWAY WEAR-PLATE AND RAIL-BRACE.

SPECIFICATION forming part of Letters Patent No. 623,177, dated April 18, 1899.

Application filed October 13, 1898. Serial No. 693,368. (No model.)

To all whom it may concern:

Be it known that I, CALVIN DAVID PAXSON, a citizen of the United States, residing at Limaville, in the county of Stark and State of Ohio, have invented certain new and useful Improvements in Railway Wear-Plates and Rail-Braces, of which the following is a full and complete specification, such as will enable those skilled in the art to which it appertains to make and use the same.

This invention relates to railway wear-plates which are inserted beneath the rails upon the usual wooden ties and which generally are provided upon their under surfaces with projections or means of anchorage to the tie and upon their upper surfaces with a shoulder or shoulders, against which the edge or edges of the rail are intended to bear; and the object of my invention is to provide a plate which shall serve to receive the rail firmly upon its upper surface and support the same against the outward lateral thrust of traffic and which shall by reason of a novel construction and arrangement of anchorage upon its under surface be so mounted upon the tie that when the said anchorage is forced thereinto it will with a peculiar degree of efficiency serve to prevent displacement or movement of the plate and the rail either laterally of said rail in the direction of the fibers of the tie or longitudinally against the fibers thereof, which two movements or tendencies toward movement of the rails are well known to exist by those skilled in matters pertaining to railroads and particularly to the track devices and equipments thereof, a further object of my invention being to in every way preserve the tie against unnecessary injury by the entering of the anchorage thereinto or its continued presence therein.

With these ends in view my invention consists of a wear-plate provided upon its upper surface with a shoulder, preferably of the form hereinafter fully described, and provided on its under surface with two or more separate series of projections ranging, respectively, longitudinally and transversely with reference to the rail above, and such projections being preferably of the form hereinafter fully described.

In the accompanying drawings, Figure 1

illustrates my improved wear-plate mounted in position upon the tie and beneath a rail, both of which are shown in transverse vertical section, with the wear-plate in edge elevation. Fig. 2 is an inverted plan view of the wear-plate, and Fig. 3 is a side elevation of the plate from the inner side.

The wear-plate A comprises a flat metallic body of any suitable thickness, usually oblong. Upon the upper surface thereof, at the outer edge, is an integral shoulder B, projecting inwardly over and approximately parallel with the plate to a point where in actual practice it will abut against the tongue 65 of the rail C. This shoulder preferably extends entirely across the plate and is so formed that the inner or free edge B' thereof and its under surface B² are adapted to receive the rail against and beneath the same, the base 70 of the rail fitting between the plate A proper and the said under surface of the shoulder B to, in effect, be firmly held thereby.

Extending vertically through the shoulder B and the plate beneath, and also through 75 the opposite corner of the plate, are spike-holes D. I have shown the customary number, but of course it is immaterial how many spike-holes are employed. In Fig. 1 I have shown the spikes E inserted through said 80 spike-holes in proper position.

Upon the under surface of the plate in a line with the longitudinal center thereof—that is to say, transversely with respect to the rail C—I form a series of projections or spurs 85 F. In the drawings I have shown four of these spurs, the same being located one almost immediately underneath and slightly within either edge of the base of the rail and one slightly within either edge of the plate A. I also form 90 upon the under surface of the said plate in a line with the transverse center thereof a second series of projections or spurs G, the middle one of which is at the exact center of the plate and two others are a suitable distance 95 apart therefrom on either side thereof. The preferred form of each of these projections or spurs is that of a sectionally rectangular lug throughout a majority of the length of the said spurs from the under surface of the 100 plate downwardly and at a suitable point beveled upon two of their faces to form cut-

ting edges F' and G', respectively. The projections or spurs F are substantially square to present a comparatively short or narrow cutting edge, while the projections or spurs 5 G are elongated to present a relatively wider cutting edge, and the opposite dimensions of the projections or spurs G are proportionately decreased.

By an examination of Fig. 2 it will be observed that the cutting edges F' of the longitudinal series of projections or spurs F range transversely of the plate, so as to cut across the fibers of the tie, and these edges F', being, as stated, substantially short or narrow—that is to say, to such a degree as their necessary efficiency of holding will permit—will cut but few of the fibers of the tie across and into which these edges F' bear, and, on the other hand, the cutting edges G' of the second or transverse series of projections or spurs G each range in a direction longitudinal of the plate, so that the said edges G' enter between the fibers of the tie, and by reason of the specified elongation and narrowing of the projections or spurs G in the manner shown these said projections or spurs G will but slightly separate the fibers of the tie between which they enter, and such separation of the fibers will occur but at the point of entrance of the 30 projections or spurs G, instead of extending throughout a considerable portion of the tie, as might be the case if these projections or spurs G were not so narrowed as to thus minimize their power of separating the fibers.

35 The operation of this device will doubtless readily be understood from the foregoing description, taken in connection with the drawings. The plate is inserted into the upper surface of the tie, beneath the rail, in any convenient manner. This is customarily done by placing the plates underneath the rails, with the under projections bearing upon the surface of the wood, and the track-laying or working locomotive is then run over the rails, which embeds the projections or spurs into the tie, and the spikes are driven to tightly hold the rails and the plate. In this operation the cutting edges of the projections or spurs F and G are forced into the wood, the first across the fibers 50 and the second between the fibers, as previously stated, and while these cutting edges, formed by the beveling of the lower portions of the projections or spurs, cause easy driving of the plate the major or upper portions 55 of the projections or spurs (which being sectionally rectangular present vertical faces) will operate to frictionally engage the wood with the efficiency of railway-spikes proportionate to the peripheral surfaces of the said 60 projections or spurs, and this will have a decided tendency to hold the plate in the tie against vertical movement caused by jolting or vibration of the rails thereon. In this usual manner of operation of driving the plates the 65 shoulder upon the upper surface will act with peculiar incidental advantage to prevent the

rail from moving during the operation aforesaid, though it will be understood that this is not the object of the construction of the said shoulder. The plate now being in position it 70 will be seen that by reason of the shoulder B, which clasps the rail, of the spikes E, holding down the said shoulder and the plate on one side and the rail itself and the plate on the opposite side, and of the rectangular projections 75 or spurs frictionally engaging the wood there will be a strong opposition to vertical movement of the rail. This is, however, not the chief function of a railway wear-plate, for apart from the primary necessity of protecting the tie from the pressure and pounding of the rails a wear-plate should operate to prevent lateral movement or yielding of the rail, and also longitudinal movement thereof. These are the chief functions of my device. 85

Referring to the question of the lateral movement or yielding of the rail against the outward thrust of the car-wheels, it will be seen, first, that this movement will be directly supported by the shoulder B, the nearest recipient of the outward thrust of the rail, and by reason of the formation and construction of the said shoulder the inner or bearing face B' thereof will abut against the tongue, in addition to the said shoulder receiving the 95 thrust of the rail, at and through the rail-base, which fits between the said shoulder and the plate, and while any shoulder will act as a stop against the base of the rail this form of shoulder B increases considerably the 100 area of resistance to the thrust of the rail. This shoulder, however, would have little power in this regard were it supported only by the spikes E or were it supported by a form of anchorage which is of itself weak 105 against lateral movement of the rail. With the cutting edges of the longitudinal series of projections or spurs F arranged to cut across the fibers of the tie the cut edges of the said 110 fibers will resist the impact of the sides of the projections or spurs F and prevent their sliding through the separated fibers of the tie, as might be the case were the cutting edges F' arranged in the opposite direction or parallel with the cutting edges G' of the projections 115 or spurs G, and it will be observed that these projections or spurs G for that reason will of themselves offer no substantial resistance to lateral movement.

Similarly to the importance of preventing 120 lateral shifting of the rails, which is well known to be the cause of many accidents, is the prevention of longitudinal movement of the wear-plates, since the rails being bound down by the spikes to the plates and in this case by the shoulder B as well the friction of the rail and the plate and of the rail-base and the spike-heads is such that without a proper anchorage there would be a tendency of the plates to move longitudinally with the 125 rails, whereas this condition should be reversed and the wear-plates should be immov-

able longitudinally to the rail and support and hold the said rail against longitudinal movement.

As my invention is preferably constructed, 5 (which I conceive to be its best form,) the second or transverse series of projections or spurs G are, as hereinbefore described, and well shown in Fig. 2, so elongated and narrowed that while entering between the fibers at their 10 points of insertion they present substantial surfaces against longitudinal movement of the plate, and by reason of said form and dimensions not only but slightly separate the fibers, as previously specified; but, moreover, 15 this leaves a substantial amount of wood between the projections or spurs G to assist such resistance, whereas if I were to reverse the direction of the cutting edges of each of the 20 projections or spurs G and make them parallel with the cutting edges of the projections or spurs F there might be so little wood or fibers of the tie between them as to make practically a long slit across the fibers of the tie centrally upon the longitudinal line of the 25 rails. The opposite directions of the projections or spurs and the relative locations thereof have also a mutually beneficial effect in that the end projections or spurs G being arranged to enter the tie nearer the side edge 30 thereof than the projections or spurs F they will have a tendency to press the fibers of the tie inwardly or toward the center thereof against the partially-separating action upon said fibers of the projections or spurs F, and, 35 moreover, the pressure of the projections or spurs F will, on the other hand, have a tendency to hold together by an outward pressure the fibers which would otherwise be more extensively separated by the said projections or 40 spurs G.

It will be seen that each of the various elements of my device operates jointly and in co-operation with each of the others to prevent these various movements of the rail, and that 45 by the peculiar arrangement of the projections or spurs I obtain a wonderfully-increased efficiency in the performance of the required functions of a perfect anchorage, and it will also be seen that the whole plate 50 will, in conjunction with and in support of the shoulder B, act as a brace, which, even upon sharp curves, will so withstand the outward tendency of the rail as to render the same safe and firm even under heavy traffic. 55 Moreover, by reason of the peculiar construction of this shoulder the rail cannot rise and ride over the same, as it often does with low purely vertical shoulders not only on curves, but also in a certain degree upon straight 60 tracks. This tendency of the rail to rise comes mainly from the jar of the train, which so vibrates the rail as constantly to raise the spikes, so that the heads thereof project appreciably above the base of the rails, in which 65 position only these spikes operate to prevent the rail from rising over the shoulder and

with the outward pressure of traffic becoming dislocated from its normal position or alignment. The outward pressure on curves is so considerable that this is most liable upon 70 such curves, particularly as the rails are usually tilted or raised higher on the outer side in accordance with the well-known principle governing curved tracks, whether on railroads or elsewhere.

I do not desire it to be understood that my invention is restricted to the exact form and shape of plate and of its elements shown in the drawings. I conceive them to represent the highest development and the best form 80 of my plate as it thus far exists. I hold, however, that my invention has a certain width of scope and is in a sense a broad invention, and that many slight changes might be made in this wear-plate as I have shown it in the 85 drawings without taking the same outside the scope of this invention.

Having fully described my invention, I claim as new and desire to secure by Letters Patent—

1. A railway wear-plate formed on its under surface with a plurality of spurs ranging along the central longitudinal line of the plate, and having beveled cutting edges directed to cut across the fibers of the tie; and 95 a second series of projections or spurs ranging along the central transverse line of the plate and having beveled cutting edges directed to enter between the fibers of the tie; whereby outward movement of the plate is 100 prevented by the first series of projections, and longitudinal creeping of the plate prevented by the second row of projections.

2. A railway-plate formed on its under surface with a central longitudinal row or series 105 of projections or spurs, substantially square in section, and beveled upon their lower portions to form cutting edges, directed to cut across the fibers of the tie, and a second row or series of projections or spurs ranging along 110 the central transverse line of the plate, and elongated longitudinally thereof, and having their lower portions beveled to form cutting edges, opposite to the cutting edge of the first series and directed to enter between the fibers 115 of the tie.

3. A railway wear-plate, formed on its upper surface with a transversely-ranging overhanging shoulder near the outer edge thereof, adapted to receive the rail-base beneath the 120 same, and the rail-tongue against the same, whereby outward movement of the rail is transmitted to the plate; and said plate being formed upon its under surface with a series of projections or spurs along the longitudinal central line of the plate, to receive 125 said outward thrust, said projections or spurs being located at either side of the transverse center of the plate between the same and the edges of said plate, and having their cutting-edges directed to cut across the fibers of the tie; and a second series of projections or spurs 130

ranging along the transverse central line of the plate, with their cutting edges directed to enter between the fibers of the tie to withstand longitudinal movement, one of said projections or spurs being located centrally of the longitudinal line of the plate and the others at either side thereof within the parallel edges of the said plate.

In testimony that I claim the foregoing as my invention I have signed my name, in presence of the subscribing witnesses, this 10th day of October, 1898.

CALVIN DAVID PAXSON.
